UNITED STATES PATENT OFFICE.

GUSTAV KREBS, OF HALLE-ON-THE-SAALE, AND ABRAHAM WEIL, OF STEINHEIM, GERMANY.

ROOFING-TILE.

SPECIFICATION forming part of Letters Patent No. 558,395, dated April 14, 1896.

Application filed March 22, 1895. Serial No. 542,849. (No model.)

To all whom it may concern:

Be it known that we, GUSTAV KREBS, fabri-
cant, a resident of Halle, and ABRAHAM WEIL,
merchant, a resident of Steinheim, in the King-
dom of Prussia and Empire of Germany, sub-
jects of the King of Prussia, have invented
certain new and useful Improvements in
Roofing-Tiles, of which the following is a
specification.

10 Our invention relates to cement roofing-tiles
of any desired shape, the lower overlapping
ledges of which are each furnished with
notches or recesses, and the upper overlapping
ledges of which are each formed with
15 tongues or teeth, so that a mutual mortise-and-
tenon joint is formed. These cement roofing-
tiles offer the great advantage that when a
number of the tiles are placed in position and
connected together to form a single layer it is
20 impossible to separate a single tile unless a
start is made by commencing to unroof at the
place where the roof was finished. Moreover,
this new tile affords a perfectly tight covering
25 on the one hand by the tenon-and-mortise
joint and on the other hand by the applica-
tion of packing to the joints, which consists
of a slit and peculiarly-angled plate of sheet
30 metal, which is inserted in the course of man-
ufacture in the tile when it is soft, the piece
35 of sheet metal providing two strips for pack-
ing, which can be bent as required.

To enable our invention to be fully under-
stood, we will proceed to describe it with ref-
erence to the accompanying drawings, in
35 which—

Figure 1 is a plan view of the under side of
one of our improved rhomboidal-shaped ce-
ment roofing-tiles. Fig. 2 is a plan view of the
upper side of the same. Fig. 3 is a section on
40 the line *a b* of Fig. 1. Fig. 4 is a front edge
view of the tile shown in Fig. 2. Fig. 5 is a plan
view and a front view of the packing-plate.
Fig. 6 is a detail perspective view of a part of
a tile provided with a packing-plate. Fig. 7
45 is a detail perspective view of a part of a
tile, showing a modification. Fig. 8 is a plan
view of the upper side of that shown in Fig. 7.
Fig. 9 is a top view of a portion of a roof pro-
vided with a layer of our improved tiles. Fig.
50 10 shows a plan view of a tile of modified form
simulating the tail of a beaver.

1 is a cement roofing-tile which has at the
upper edges of its flat upper surface two ledges
2 and 3, having on their inner sides trapezoidal
indentations 4, providing similarly-formed in-
55 terlocking teeth or tongues 4^a. The lower
edges of the flat lower surface are similarly
provided with ledges 5 and 6, which engage
over the ledges of the upper surface and are
furnished with notches or recesses 7, extend-
60 ing toward their inner sides to receive the in-
terlocking teeth or tongues.

In Figs. 7 and 8 we show a modification in
the form of the ledges 2, 3, 5, and 6, which may
be of plane tongue *b* and groove *a* shape. We
65 also show rounded front upper edges *c*. On
the flat lower surfaces of the tiles are ribs 8,
which impart to the tile increased strength
and resistance. For the purpose of suspending
70 the tiles from the roof-lath *d* they are fur-
nished with noses or lugs 9 in the usual man-
ner. The right-hand blunt corner of the tile
is furnished with a joint packing-plate, (shown
in Fig. 5,) the construction of which plate will
75 now be described.

A piece 10 of sheet metal is cut to the extent
of about one-half into two strips 11 and 12,
and of these strips the strip 11 is cut shorter
than the strip 12. Furthermore, the shorter
80 strip 11, as also the end 13 of the piece 10, it-
self are bent at an angle so that half the joint-
packing—that is to say, as far as *x* in Fig. 5—
has the form of the letter **U**. This joint-packing
85 has its portion 13 pressed into the right-
hand blunt corner of the tile in the course of
the manufacture of the latter, so that the bent
strip bounds the blunt corner, while the longer
strip 12 projects free.

The mode of employment and action of the
new tile may be explained as follows: The
90 tiles are suspended by their lugs or noses from
the roof-lath *d* in the usual manner and the
strips 11 of the tiles curved downward some-
what, as shown in Figs. 1, 6, 7, and 8. Upon
the second tile being placed in position, the
95 joint formed by the two blunt corners of the
tiles is closed by the projecting portion 11,
which acts as a spring, while the portion of the
joint which is formed by the ledges 5 and 6 is
made tight by the somewhat curved portion 12
100 and the upper part of the joint-packing plate.

Having thus described our invention, the

following is what we claim as new therein and desire to secure by Letters Patent:

1. A roofing-tile comprising upper and lower flat surfaces, the upper ledges on the upper surface formed with indentations and teeth, and the lower ledges on the lower surface formed with recesses for the teeth; substantially as described.

2. A roofing-tile comprising a packing-plate

formed with two strips 11 and 12, and a bent 10 end 13; substantially as described.

In witness whereof we have hereunto set our hands in presence of two witnesses.

GUSTAV KREBS.
ABRAHAM WEIL.
